UNITED STATES PATENT OFFICE.

AMOS G. CANBY, OF DETROIT, MICHIGAN.

ORNAMENT FOR THE RADIATOR-CAPS OF AUTOMOBILES.

1,275,384.

Specification of Letters Patent. Patented Aug. 13, 1918.

Application filed June 18, 1917. Serial No. 175,357.

To all whom it may concern:

Be it known that I, AMOS G. CANBY, a citizen of the United States of America, residing at Detroit, in the county of Wayne 5 and State of Michigan, have invented certain new and useful Improvements in Ornments for the Radiator-Caps of Automobiles, of which the following is a specification, reference being had therein to the accompanying drawings.

This invention relates to ornaments for the radiator caps of automobiles and consists in the matters hereinafter set forth, and more particularly pointed out in the appended 15 claims.

In the drawings,

Figure 1 is a view in perspective of a device that embodies features of the invention;

Fig. 2 is a view in detail of the upper portion of a staff thereof;

Fig. 3 is a view in transverse section of the wing of Fig. 1 adjacent to Fig. 3;

Fig. 4 is a view in transverse section of the wing adjacent thereto in Fig. 1, and

Fig. 5 is a view in section showing the longitudinal curvature of one of the blades of the device, and indicating the reverse curvature of the other blade in dotted lines.

As herein shown, a spindle 1 is detachably secured in any suitable manner to the cap 2 of an automobile. A base 3 thereon affords a thrust bearing for the lip 4 turned out from the lower margin of a blade 5 of suitable sheet material. The latter is slit at 30 intervals along the center and has hinge portions 6 struck up through which the spindle is thrust to steady the blade. The wings of the member 5 are oppositely curved longitudinally as indicated in Fig. 5 and preferably are each concaved or dished transversely, so that they present opposite faces of unequal resistance to the wind and hence cause the device to spin rapidly. The upper marginal portion 7 of each wing may 40 be bent as a flange on the concave face of the wing.

At the upper end portion of the spindle 1 there is a reduced bearing or journal head 8 over which a lip 9 of an upper blade 10 is 50 secured rotatably by any retaining head such as a ball 11 which is apertured to go on to a still further reduced end portion 12 where it is secured suitably. The hinge portions 13 struck up between transverse slits of the 55 central part of the upper blade 10 form steady means on the spindle and the

wings thereof, which are oppositely curved longitudinally to cause rotation of the blade in one direction, the blade being reversely disposed to the wings of the member 5, so 60 that the blade turns in an opposite direction to the other blade when moved through the air or struck by the wind.

Suitable ornamentations of the wings, as by representations of flags or emblems thereon, cause the device to present a very pleasing appearance, as the device looks the same from all directions, when in motion. By placing the same design upon the corresponding faces of the wings, as for example, 70 the British flag on the convex faces, and another design, as for example, the French tricolor, upon the concave faces of the wings of a blade, the effect is of two flags flying from opposite sides of the spindle, regardless 75 of the point of view.

Obviously, changes in the details of construction may be made without departing from the spirit of my invention and I do not care to limit myself to any particular form 80 or arrangement of parts.

What I claim is:—

1. An ornament comprising an upright spindle adapted to be secured to the cap of an automobile radiator, a symmetrically disposed lower blade journaled on the spindle and provided with oppositely extending wings, and an upper blade rotatable on the spindle and provided with oppositely extending wings, the wings of the blades being 85 curved to cause the blades to rotate in opposite directions under the influence of air through which the blades are moved.

2. An ornament comprising an upright spindle adapted to be secured to the cap of 90 an automobile radiator, a pair of blades mounted to revolve on the spindle under the influence of air moving past the spindle, each provided with oppositely disposed and convexed wings, corresponding sides of the 100 wings of the blade having similar designs whereby the blades present different designs on the sides of the spindle when the blade is spinning, and the blades being disposed to turn in opposite directions under the influence of air through which the blades are moved.

3. An ornament comprising an upright spindle, a base forming a thrust bearing on the lower end portion of the spindle, there 110 being a reduced upper portion on the spindle forming an upper thrust bearing, a lower

blade having oppositely disposed and curved wings extending in either direction from the medial line thereof, an apertured lug on the lower margin of the blade engaging over the spindle and riding on the face of the thrust bearing, hinged portions on the blade formed by transverse slits in the body thereof, curved to form bearings on the spindle, an upper blade having oppositely disposed equal wings, the curved surfaces of which are disposed oppositely to the corresponding lower blades whereby the upper blades rotate in opposite direction to the lower blades,

an upper inturned apertured lug on the upper blade engaging over the reduced portion of the spindle and bearing against the upper thrust shoulder formed thereby, and hinged portions in the blade body formed by transverse slits, and thrust out and bent to engage over the spindle.

In testimony whereof I affix my signature in the presence of two witnesses.

AMOS G. CANBY.
